Primary Examiner — Catherine Tuttle(74) *Attorney, Agent, or Firm* — CIONCA Law Group
P.C.; Marin Cionca**CLAIM**

The ornamental design for a batting practice apparatus, substantially as shown and described.

DESCRIPTION

FIG. 1 is a top and right side perspective view of a batting practice apparatus showing the new design in a first and relaxed state;

FIG. 2 is a left side elevation view thereof, the right side view being evident from the several figures shown;

FIG. 3 is a top plan view thereof;

FIG. 4 is a back elevation view thereof;

FIG. 5 is a front elevation view thereof;

FIG. 6 is a top plan view thereof, in a second and compressed state; and,

FIG. 7 is a top plan view thereof, in a third and expanded state.
